UNITED STATES PATENT OFFICE.

LORETTO A. COSTELLO, OF PHILADELPHIA, PENNSYLVANIA, ASSIGNOR, BY MESNE ASSIGNMENTS, TO SCOTT & WILLIAMS, INCORPORATED, OF CAMDEN, NEW JERSEY, A CORPORATION OF NEW JERSEY.

KNITTED WEB AND STOCKING MADE THEREFROM.

1,025,125.

Specification of Letters Patent.

Patented May 7, 1912.

Application filed June 17, 1910. Serial No. 567,505.

To all whom it may concern:

Be it known that I, LORETTO A. COSTELLO, a citizen of the United States, residing in Philadelphia, Pennsylvania, have invented 5 certain Improvements in Knitted Webs and Stockings Made Therefrom, of which the following is a specification.

The object of my invention is to provide a knitted fabric, and especially a tubular 10 knitted fabric, having, side by side, portions, one consisting of relatively loose or open web and another of closer or stiffer web, my invention being intended particularly for application to stockings having a 15 relatively loose or open web in the top of the foot, instep, front of the ankle, and leg, and having a closer and firmer web in the toe, sole, and heel, this closer web also, by 20 preference, extending up the back of the ankle to simulate the ordinary "high spliced" heel generally employed in stockings of open texture.

In the accompanying drawings—Figure 25 1 is a side view of the foot and ankle portion of a stocking produced in accordance with my invention; Fig. 2 is an exaggerated view of part of the web at one side of the stocking, this view being taken on the line $a-a$, Fig. 1; Fig. 3 is a diagram representing the needles of a circular knitting machine upon which my improved fabric can 30 be produced; Fig. 4 is a view similar to Fig. 2, but illustrating another type of my improved fabric, and Figs. 5 and 6 are also 35 views similar to Fig. 2, but illustrating special forms of my improved web.

In the stocking shown in Fig. 1, the leg, the front of the ankle, the instep and the top of the foot are composed of relatively 40 loose-knitted or open-work web, as is desirable in stockings for summer wear, but the toe, the sole, the heel, and the upward extension of the heel into the ankle are composed of more closely knitted and firmer 45 web in order to better resist the wear to which they are subjected in use. If, however, an attempt is made to attain this result simply by tightening the stitches in that portion of the stocking in which the more 50 closely knitted web is desired, this portion of the stocking web would be shorter than the adjoining portion in which the web was knitted loosely or with slack stitches, and a distortion of the stocking would necessarily

result. In order to overcome this objection 55 I increase the number of courses in a given length of the closely knitted web as compared with a corresponding length of the loosely knitted web, and I am thereby enabled to produce a symmetrical web while 60 attaining all of the advantages of loose knitting in one portion of said web and close knitting in the other portion.

As will be observed in reference to Fig. 2, there are, in the loosely knitted portion of the 65 web, five courses and in the closely knitted portion ten courses. In order to effect this result compensating courses are formed in the closely knitted portion only of the web, and I will describe one method of accomplishing this result in a circular knitting machine, reference being had to Fig. 3 of the drawing, in which the circle of dots represents the needles of the machine, those needles around that half of the machine 70 from a to b being acted upon by short draft cams so as to produce close or tight stitches in the portion x of the web, and those needles around the machine from c to d being acted upon by long draft cams so as 75 to produce longer or slacker stitches in the portion y of the web.

In order to produce a fabric of the character shown in Fig. 2, the knitting may start, say at a and proceed in the direction 85 a, b, c, d , the machine first knitting around and around so as to produce two complete courses 1 and 2 composed in part of close 90 stitches in the web x and in part of slack stitches in the web y . The machine then knits to-and-fro from a to b and back from b to a in order to produce two more courses 95 3 and 4 of closely knitted web in the portion x of the fabric, the operations being then repeated with the result that for every two courses of stitches in the slack-knitted portion y of the web there will be four courses of stitches in the close-knitted portion x .

If a greater disparity in the number of 100 courses of stitches in the two portions of the web is desired, every course of around and around knitting may alternate with a to-and-fro knitting operation to produce the excess courses from a to b and from b to a , 105 which will result in a close-knitted portion of the web having three times as many courses of stitches as there are in the slack-

knitted portion, or even more than this number may be produced, but in that case it is preferable to produce the selvage stitches at the ends of the to-and-fro courses on different needles in order to prevent the formation of large eyelet holes where said selvage stitches are produced. If, for instance, there are four reciprocating courses, as shown in Fig. 5, the first reciprocating course 2 may end and the second reciprocating course 3 may begin in the wale B' knitted on the needle b', the second course 3 ending and the third reciprocating course 4 beginning in the corresponding wale at the opposite side of the web. The third reciprocating course 4 may end and the fourth reciprocating course 5 may begin in the wale B knitted on the needle b, said fourth course 5 ending and the following continuous course 1 beginning in the corresponding wale at the opposite side of the web, or the first reciprocating course 2 may, as shown in Fig. 6, end and the second reciprocating course 3 may begin in wale B knitted on the needle b, and the third reciprocating course 4 may end and the fourth reciprocating course 5 may begin in wale B' knitted on the needle b', there being a corresponding re-arrangement of the stitches at the opposite side of the web. In the first case, the needle b will be elevated or out of action at the ending of the first course 2 but will be picked into action before the completion of the third course 4, and in the second case the needle b will be in action at the end of the first course 2 and may be picked out of action before the ending of the third course 4, the needle a being correspondingly manipulated in respect to the intervening courses.

It is preferable, to have such a number of courses of stitches in the tight portion of the knitted web that the same will be somewhat longer than the slack knitted portion, whereby, in use, the tension will be exerted upon the latter, which can stretch most readily, this stretching serving to contract the diameter of the tube which is advisable in the case of a stocking foot or ankle.

If desired, instead of knitting around-and-around to produce continuous circular courses of stitches comprising both slack-knitted and close-knitted portions of the web, the fabric may as shown in Fig. 4 be produced by to-and-fro knitting entirely in connection with a plurality of yarn guides, one for supplying the needles upon which the close knitting is produced, and the other for supplying the needles upon which the knitting is slack, for instance, to-and-fro knitting may be carried on upon the needles from c to d and from d to c to produce the slack knitted portion y of the web, and to-and-fro knitting may be carried on upon the needles from a to b and from b to a to produce the closely knitted portion x of the web, these two portions being united together at the meeting points by feeding yarn of one web to a needle or needles of the section which produces the other web, for instance, the yarn guide for the needles a b may, when moving in one direction, pass beyond the needle b and apply its yarn to the needle c which has been raised for the purpose, and in moving in the other direction it may pass beyond the needle a and apply its yarn to the needle d which has been raised for the purpose, and, if desired, also, the yarn guide which supplies the needles c to d may pass beyond the needles c and d and apply its yarn to the needles b and a in like manner. By this means loops will be produced for tying together the terminal wales of the two webs, as shown in Fig. 4. In this case there should be a greater number of reciprocating or to-and-fro knitting operations upon the needles a b than upon the needles c d, in order to provide the compensating courses of stitches in the closely knitted portion of the web, for instance, as shown in Fig. 4, there may be four courses 1, 2, 3 and 4, knitted upon the needles a b for every two courses 1 and 2 knitted upon the needles c d, in which case the yarn guide for the needles c d will be held stationary or said needles c and d will not be operated during the time that two courses of to and-fro knitting are being knitted upon the needles a b, thus, knitting may be carried on upon the needles from c to d, simultaneously with the knitting upon the needles from a to b, and upon the needles from d to c, simultaneously with the knitting upon the needles from b to a, knitting upon the needles c d being then arrested while knitting upon the needles from a to b and from b to a is continued, the operations being then resumed as before.

A machine such as that designed for the production of stockings with seamless heels and toes lends itself very readily to the production of a stocking in accordance with my invention, since such machine is already provided with means for producing reciprocating or to-and-fro knitting on that half of the tube upon which the heels and toes are formed, and the production of the compensating courses in the sole portion of the foot, or the rear of the ankle, does not interfere with the proper operation of the picking mechanism whereby the needles are put into and out of action in the formation of said heel and toe pockets.

Although I have described my invention as intended particularly for use in knitting stockings, it is not limited thereto but is applicable to the knitting of ordinary tubular webs upon either circular or straight machines, or even to the knitting of flat webs upon flat bed machines.

A succession of stitches contained in a

slack-knitted or a tight-knitted portion of the web I term a course, whether it extends from end to end of a row or forms part of a continuous circular course.

5. I claim:

1. A knitted web having, side by side, wales, some composed of courses of relatively slack stitches and others composed of courses of tighter stitches, a given length 10 of web having a greater number of the tight courses than of the slack courses.

2. A knitted web having, side by side, wales, some composed of courses of relatively slack stitches and others composed of 15 courses of tighter stitches, the slack knitted courses having corresponding tight knitted courses, and other courses being contained in the tight knitted wales only.

3. A knitted web having, side by side, 20 wales, some composed of courses of relatively slack stitches and others composed of courses of tighter stitches, the slack knitted courses having corresponding tight knitted courses, and other courses being contained 25 in the tight knitted wales only, and said latter courses having selvaged ends.

4. A knitted web having, side by side, wales, some composed of courses of relatively slack stitches and others composed of 30 courses of tighter stitches, the slack knitted courses having corresponding tight knitted courses, and other courses being contained in the tight knitted wales only, and said latter courses having selvaged ends contained 35 in different wales of the web.

5. A tubular knitted web having, side by side, wales, some composed of courses of relatively slack stitches and others composed of courses of tighter stitches, some of the 40 courses extending completely around the tube and presenting both slack and tight stitches, and certain of the tight knitted courses being confined to a portion only of the tube.

45. 6. A tubular knitted web having, side by side, wales, some composed of courses of relatively slack stitches and others composed of courses of tighter stitches, some of the courses extending completely around 50 the tube and presenting both slack and tight stitches, and certain of the tight knitted courses being confined to a portion only of the tube and having selvaged ends.

7. A tubular knitted web having, side by 55 side, wales, some composed of courses of relatively slack stitches and others composed of courses of tighter stitches, some of the courses extending completely around the tube and presenting both slack and tight 60 stitches, and certain of the tight knitted courses being confined to a portion only of the tube and having selvaged ends in different wales of the web.

8. A stocking having a seamless heel and 65 toe and having, in the top of the foot, wales

composed of courses of relatively slack stitches and in the sole a greater number of courses of tighter stitches than there are courses in the top of the foot.

9. A stocking having a seamless heel and 70 toe and having, in the top of the foot, and in the front of the ankle, wales composed of courses of relatively slack stitches and in the sole and rear of the ankle, wales composed of a greater number of courses of tighter stitches than there are courses in 75 the top of the foot and front of the ankle.

10. A stocking having a seamless heel and toe and having, in the top of the foot, wales composed of courses of relatively slack 80 stitches, and in the sole, wales composed of courses of tighter stitches, some of the courses extending completely around the foot, and presenting both slack and tight 85 stitches and certain of the tight knitted courses being contained only in the sole.

11. A stocking having a seamless heel and toe and having, in the top of the foot, wales composed of courses of relatively slack 90 stitches, and in the sole, wales composed of courses of tighter stitches, some of the courses extending completely around the foot, and presenting both slack and tight 95 stitches and certain of the tight knitted courses being contained only in the sole and having selvaged ends.

12. A stocking having a seamless heel and toe and having, in the top of the foot, wales composed of courses of relatively slack 100 stitches, and in the sole, wales composed of courses of tighter stitches, some of the courses extending completely around the foot, and presenting both slack and tight stitches and certain of the tight knitted courses being contained only in the sole and having 105 selvaged ends in different wales of the web.

13. A stocking having a seamless heel and toe and having, in the top of the foot and front of the ankle, wales composed of courses of relatively slack stitches, and in the sole and rear of the ankle, wales composed of courses of tighter stitches, some of the courses extending completely around the foot and ankle and presenting both slack 110 and tight stitches, and certain of the tight 115 knitted courses being contained only in the sole and rear of the ankle.

14. A stocking having a seamless heel and toe and having, in the top of the foot and front of the ankle, wales composed of 120 courses of relatively slack stitches, and in the sole and rear of the ankle, wales composed of courses of tighter stitches, some of the courses extending completely around the foot and ankle and presenting both slack 125 and tight stitches, and certain of the tight knitted courses being contained only in the sole and rear of the ankle, and having selvaged ends.

15. A stocking having a seamless heel and 130

toe and having, in the top of the foot and front of the ankle, wales composed of courses of relatively slack stitches, and in the sole and rear of the ankle, wales composed of courses of tighter stitches, some of the courses extending completely around the foot and ankle and presenting both slack and tight stitches, and certain of the tight knitted courses being contained only in the

sole and rear of the ankle, and having selvaged ends in different wales of the web.

In testimony whereof, I have signed my name to this specification, in the presence of two subscribing witnesses.

LORETTO A. COSTELLO.
